FEELER MECHANISM FOR LOOMS.

1,387,327.

Specification of Letters Patent.

Patented Aug. 9, 1921.

Application filed July 31, 1920. Serial No. 400,451.

To all whom it may concern:

Be it known that I, ISAAC SNOW, a citizen of the United States, and a resident of Lawrence, county of Essex, and State of Massachusetts, have invented an Improvement in Feeler Mechanism for Looms, of which the following description, in connection with the accompanying drawings, is a specification, like characters on the drawings 10 representing like parts.

This invention relates to feeler mechanisms for looms, and more particularly to feeler mechanisms commonly known as "side swipe" feelers, wherein the feeler is 15 moved in a direction longitudinally of the shuttle upon the occurrence of substantial exhaustion of filling.

In this general type of feeler mechanisms it is desirable that the feeler partake of its 20 side swipe or movement longitudinally of the shuttle when the filling reaches a predetermined degree of exhaustion. It may happen at times that the feeler will not promptly respond to the forces tending to 25 move it longitudinally of the shuttle when the filling is substantially exhausted, and one of the important features of the present invention consists in a feeler and a feeler displacer which acts upon the feeler and 30 tends to move it longitudinally of the shuttle on a detecting beat.

While the feeler mechanism of the present invention is herein shown as comprising a feeler which is supported to enter the shuttle 35 in a direction inclined to the longitudinal axis thereof, on a detecting beat, it is to be understood that the invention is not restricted to this particular type of feeler, but that the feeler displacer may be associated 40 with any type of side swipe feeler to assist in or insure its movement longitudinally of the shuttle when the filling is substantially exhausted on a detecting beat.

The feeler of the present invention is provided with a toothed or roughened end 45 which engages a surface within the shuttle on a detecting beat, and movement of the feeler longitudinally along the filling carrier or bobbin in the shuttle is prevented by 50 engagement of the teeth with the filling on a detecting beat until substantial exhaustion of filling. When substantial exhaustion occurs, however, and a new supply of filling is required, the feeler should respond quickly,

A further feature of the present invention, 55 therefore, consists in a feeler provided with a toothed engaging end and a feeler displacer which has an end which is movable along the surface engaged by it on each detecting beat, but is held from such movement 60 by the feeler which is held by the filling until substantial exhaustion.

The above features of the invention and other novel elements and combinations of parts will be hereinafter described in connection with the accompanying drawings which show one good, practical form of the invention, but it is to be understood that the invention is not restricted to the details shown which, of course, may be varied within the scope of the invention as defined by the claims.

In the drawings:

Figure 1 is a perspective view of a feeler side of a loom, showing more particularly 75 the feeler mechanism and its associated parts;

Fig. 2 is an enlarged detached plan view showing the action of the feeler mechanism when a working supply of filling is present 80 in the shuttle on a detecting beat;

Fig. 3 is a view similar to that of Fig. 2 showing the action of the feeler mechanism when the filling is substantially exhausted on a detecting beat;

Fig. 4 is a detached detail showing the actuator or slide through which the longitudinal movement of the feeler along the filling carrier or bobbin is made effective for replenishing filling.

The loom frame 1 may be of usual character. Connected to the loom frame are the brackets or supports 2, one at each side of the loom in which is mounted the transverse or rock shaft 3. Rising from the rock shaft 95 3, which may be of usual construction, is the arm 4 to which is pivoted at 5 the latch 6. The latch 6 has a rear engaging end portion 7 adapted to be engaged at times by an operating member 8 which may conveniently be formed as part of or be connected to the cam follower. The engaging end 7 of the latch is under control of the feeler mechanism so that when the feeler is moved longitudinally along the filling carrier or 100 bobbin on a detecting beat, the end 7 of the latch 6 will be placed in the path of movement of the operating member and effect 105

replenishment of filling in a manner well understood by those skilled in the art. In the present instance of the invention the rear engaging end 7 of the latch is pivotally mounted at 9 and has a finger 10 which overlies the arm 11 of a bell crank pivoted at 12 to a support 13 which may be conveniently carried by the loom frame and which, in the present instance, is connected by a bolt 14 to a supporting lug 15. The other arm 16 of the bell crank lever is connected to a transmitter 17, the construction being such that when the transmitter 17 is appropriately moved, in the present instance to the right, Fig. 1, the bell crank lever will position the end 7 of the latch and the operating member 8 relatively for engagement as the operating member moves frontwardly.

Extending from the loom frame is the shipper stand 18 which may be provided with an arm for supporting the feeler and feeler displacer, as will presently appear. In the present instance the shipper stand has an outwardly extending arm 19 provided with a slot 20 to which is secured the supporting bracket 21. Mounted upon the supporting bracket 21 is the feeler stand 22 which may be adjustably secured to the bracket by the bolts 23 which pass through a slot 24 in the feeler stand, the construction being such that the feeler stand may be appropriately adjusted, as usual, on its support.

The feeler is mounted upon the feeler stand and so also is the feeler displacer, and in the present instance the feeler stand is provided with a front bearing portion and a rear bearing portion through which the feeler and feeler displacer extend. The front bearing portion may comprise the two brackets 25 and 26 which preferably overlap each other, as indicated in Fig. 1, and each of the brackets is provided with a slot 27 through which passes a securing bolt 28. Each of the brackets is provided with an upstanding lug which forms a bearing for the front end portion of the feeler and feeler displacer, respectively. In the present instance, the bracket 26 has the lug 29 which is provided with an opening through which extends the stem 30 of the feeler 31. Similarly, the bracket 25 is provided with the up-standing lug 32 through which extends the stem 33 of the feeler displacer 34.

The rear portion of the feeler stand 22 has rising therefrom a flange 35 which has a slot 36 and which may be conveniently formed as part of a plate 37 secured by suitable bolts or pins 38 to the feeler stand.

The feeler 31 and the feeler displacer 34 extend through the slot 36 of the rear bearing or up-standing flange 35 and interposed between a shoulder 39 formed on the feeler 65 and the up-standing flange 29 is a spring 40

which normally acts to force the feeler into its rearward feeling position. A stop, such as the pin 41, for instance, limits the rearward movement of the feeler. Similarly, the feeler displacer 34 is provided with a shoulder 42 between which and the up-standing flange 32 is interposed a spring 43 normally tending to force the feeler displacer into its rearward position. The details just described form a convenient construction for mounting the feeler and feeler displacer, but the invention is not restricted thereto because the essentials in these respects are that the feeler and feeler displacer may be normally under the influence of yielding means for holding them in their rearward position.

Mounted at the rear part of the feeler stand is a slide or actuator 44 through which the feeler and, it may be, the feeler displacer, extend. The slide or actuator 44 may be variously formed, but in the present instance it comprises a base portion 45 having a slot 46 which may embrace the rear bearing 35 and in connection therewith act 90 as guiding means for the actuator or slide as it is moved. The up-standing flange or plate 47 of the actuator or slide 44 is likewise provided with a slot 48 through which extend the feeler 31 and the feeler displacer 34. The actuator or slide 44 is connected to the transmitter 17 at 49, so that sliding movement of the slide or actuator 44 in a direction transversely of the loom, will appropriately operate the transmitter 100 to effect replenishment of filling through a train of mechanism, or other suitable means, such as hereinbefore described.

In the present instance of the invention the feeler is shown as of the inclined type, that is, it is supported or mounted to enter the shuttle on a detecting beat in a direction inclined to the longitudinal axis of the shuttle or the path of lay movement. The feeler displacer 34 is likewise shown, in the present instance of the invention, as supported in a position inclined to the longitudinal axis of the shuttle or path of lay movement, and preferably at a somewhat greater angle of inclination than is the feeler. The slot 48 in the slide or actuator 44 is of appropriate length to permit the feeler and feeler displacer to be moved frontwardly on a detecting beat while the end of the feeler is held from movement longitudinally of the shuttle by the filling, without causing movement of the slide or actuator 44. When, however, the feeler is moved in a direction longitudinally of the shuttle or along the filling carrier or bobbin, on a detecting beat, such movement of the feeler causes the slide or actuator 44 to be moved and, through the train of mechanism described, effect replenishment of filling.

The lay 50 is provided with the shuttle 130

box 51 into which is received the shuttle 52 provided with the filling carrier or bobbin 53 on which the filling is wound. The front wall of the shuttle box is provided with an 5 opening 54, as usual in this class of looms, and similarly the adjacent or front wall of the shuttle is provided with an opening 55 which registers with the opening 54 when the shuttle is in the detecting box, so that 10 the feeler may enter and feel for the filling.

The rear end of the feeler 31 is roughened or provided with a series of teeth 56 which engage a surface within the shuttle on each detecting beat. When this surface is formed 15 by a working supply of filling, the roughened or toothed end 56 of the feeler holds the feeler from movement longitudinally along the filling carrier as the lay beats up. When, however, the filling is substantially 20 exhausted, the holding action of the toothed end of the feeler is ordinarily not sufficient to prevent movement of the feeler in a direction longitudinally of the shuttle on a detecting beat. It may happen at times, 25 however, that the surface of the bobbin may be in such condition that the feeler will not readily move longitudinally of the shuttle and along the surface of the filling carrier. If it does not, a mis-pick or partial pick 30 may occur and imperfect cloth be woven. The feeler displacer, therefore, is so constructed and arranged as to bear against the feeler on a detecting beat and exert a force thereupon tending to move the feeler longitudinally of the shuttle. This tendency of 35 the feeler displacer to move the feeler longitudinally of the shuttle is overcome by the holding action of the toothed end of the feeler and its engagement with the filling 40 when a working supply is present on a detecting beat, but when the filling is substantially exhausted, the tendency of the displacer to move the feeler longitudinally along the filling carrier or bobbin is rendered effective even though the end of the 45 feeler may be obstructed in its movement by the character of the surface engaged by it.

The feeler displacer, in the present instance of the invention, has an end portion 50 which is untoothed so that under the frontward pressure of a surface upon the end of the displacer on each detecting beat, the tendency of the displacer is to move longitudinally of the shuttle and exert a lateral 55 force upon the feeler. The engaging end of the feeler displacer may be otherwise formed, the construction should be such, however, that under the frontward pressure exerted upon the feeler displacer on a de- 60 tecting beat, the feeler displacer may not be obstructed in its tendency to move longitudinally of the filling carrier or bobbin and to exert a displacing force upon the feeler.

65 To insure that the teeth of the feeler may

engage the surface within the shuttle before the end of the feeler displacer engages such surface, it is preferable to extend the feeler rearward slightly beyond the end of the feeler displacer, as indicated by dotted lines 70 in Figs. 1 and 2. This gives an opportunity for the toothed end of the feeler to sink into the filling and get a hold thereon before the lateral displacing force of the feeler displacer is exerted upon the feeler. 75

Applicant believes himself to be the first in the art to provide a feeler displacer which, under the frontward pressure of a surface carried by the lay, acts upon and tends to move the feeler longitudinally of the shuttle 80 on a detecting beat and which acts to effect such movement should the feeler be obstructed in its movement longitudinally of the shuttle when filling is substantially exhausted on a detecting beat. Therefore, 85 while applicant has shown the feeler displacer as engaging the filling or filling carrier on a detecting beat, it is within the scope of the invention to have the feeler displacer engaged by some other surface 90 carried by the lay on a detecting beat, the essentials in this respect being that under the frontward pressure against the feeler displacer, the latter will have a tendency to move longitudinally of the shuttle and will 95 transmit that tendency to the feeler.

Claims:

1. In a feeler mechanism for looms, the combination of a feeler that is mounted to enter the shuttle in a direction inclined to the longitudinal axis of the filling carrier or bobbin and is held from movement longitudinally along the filling carrier or bobbin on a detecting beat by engagement with the filling until substantial exhaustion thereof, a feeler displacer which is mounted to enter the shuttle in a direction inclined to the longitudinal axis of the shuttle and which tends to slide longitudinally of the filling carrier or bobbin under the frontward pressure on each detecting beat but is held from such movement by the feeler until the filling is substantially exhausted and then acts against the feeler to insure its movement longitudinally of the shuttle, and means for replenishing the filling when the feeler is so moved. 105 110 115

2. In a feeler mechanism for looms, the combination of a feeler that is supported to enter the shuttle in a direction inclined to the longitudinal axis of the shuttle, a feeler displacer that is also supported to enter the shuttle in a direction inclined to the longitudinal axis thereof, and under the frontward pressure upon it on a detecting beat tends to move the feeler longitudinally of the shuttle, and means for replenishing the filling when the feeler is moved along the filling carrier longitudinally thereof. 120 125

3. In a feeler mechanism for looms, the 130

- combination of a feeler that is supported to enter the shuttle in a direction inclined to the longitudinal axis of the shuttle, a feeler displacer that is also supported to enter the shuttle in a direction inclined to the longitudinal axis thereof at a greater angle than the feeler, and under the forward pressure upon it on a detecting beat tends to move the feeler longitudinally of the shuttle, and means for replenishing the filling when the feeler is moved along the filling carrier longitudinally thereof.
4. In a feeler mechanism for looms, the combination of a feeler that is supported for movement toward and from the front of the loom and in a direction longitudinally of the shuttle, a feeler displacer that is supported for movement in a direction longitudinally of the shuttle and in an inclined position relative to the path of lay movement and bears upon and tends to displace the feeler in a direction longitudinally of the shuttle on a detecting beat, and means for replenishing the filling when the feeler is so moved.
5. In a feeler mechanism for looms, the combination of a feeler that is supported for movement toward and from the front of the loom and in a direction longitudinally of the shuttle and provided with a toothed or roughened engaging end which holds the feeler from movement longitudinally of the shuttle by engagement with the filling until substantial exhaustion thereof on a detecting beat, a feeler displacer having an end to engage a surface carried by the lay on each detecting beat and that is constructed and arranged to be movable along said surface longitudinally of the shuttle on each detecting beat under the forward pressure upon it and exert a force upon the feeler tending to move it in a direction longitudinally of the shuttle, and means for replenishing the filling.
6. In a feeler mechanism for looms, the combination of a feeler that is supported for movement toward and from the front of the loom and in a direction longitudinally of the shuttle and provided with a toothed or roughened engaging end which holds the feeler from movement longitudinally of the shuttle by engagement with the filling until substantial exhaustion thereof on a detecting beat, a separately supported feeler displacer having a non-holding end to engage a surface within the shuttle and adapted to be displaced in a direction longitudinally of the shuttle by the forward pressure of said surface on each detecting beat and to force the feeler longitudinally of the shuttle when it fails to be held from such movement by the filling, and means for effecting replenishment of filling.
7. In a feeler mechanism for looms, the combination of a feeler and a feeler dis-

placer both of which are supported to enter the shuttle in a direction inclined to the longitudinal axis of the shuttle, teeth carried by the feeler which engage a surface within the shuttle on a detecting beat before the feeler displacer engages the surface, and means for effecting replenishment of filling when the feeler is moved along the filling carrier on a detecting beat.

8. In a feeler mechanism for looms, the combination of a toothed feeler and an untoothed feeler displacer, both of which are supported to enter the shuttle in a direction inclined to the path of the lay, the forward pressure upon the untoothed end of the feeler displacer tending to move the feeler displacer and feeler longitudinally of the shuttle on a detecting beat, and means for replenishing the filling when the feeler is so moved.

9. In a feeler mechanism for looms, the combination of a feeler that is supported for movement toward and from the front of the loom and also in a direction longitudinally of the shuttle, a feeler displacer supported in an inclined position relative to the feeler to abut against the rear portion of the feeler and having a non-toothed filling engaging end which receives the forward pressure upon it as the lay beats up and tends to move the feeler longitudinally of the shuttle on each detecting beat and insures such movement of the feeler when the filling is substantially exhausted.

10. In a feeler mechanism for looms, the combination of a feeler that is mounted for movement toward and from the front of the loom and in a direction longitudinally of the shuttle, means constructed and arranged for movement longitudinally of the shuttle by the forward pressure upon it on each detecting beat and at such times acting upon the feeler to impart its movement longitudinally of the shuttle to the feeler when the filling due to substantial exhaustion thereof fails to hold the feeler on a detecting beat, and means for effecting replenishment of filling when the feeler is so moved.

11. A feeler mechanism for looms comprising, in combination, a feeler that is mounted for movement toward and from the front of the loom and in a direction longitudinally of the shuttle and is held from movement longitudinally of the shuttle by engagement with the filling until substantial exhaustion thereof, a feeler displacer mounted for movement longitudinally of the shuttle and that receives the impact of a surface on the lay during each detecting beat and tends to move in a direction longitudinally of the shuttle but is held from such movement by the feeler until the filling is substantially exhausted and thereupon acts upon the feeler to insure its movement longitudinally along the filling carrier, and means for

effecting replenishment of filling when the feeler is moved longitudinally along the filling carrier.

12. In a feeler mechanism for looms, the combination of a feeler that is mounted for movement toward and from the front of the loom and in a direction longitudinally of the shuttle and is held from such longitudinal movement by engagement with the filling 10 until substantial exhaustion thereof, a feeler displacer which is mounted to move frontwardly and longitudinally of the shuttle and to receive a frontward pressure of a surface within the shuttle which tends to move the feeler displacer longitudinally of the shuttle on each detecting beat and at such times is held from movement longitudinally of the shuttle by the feeler until the filling is substantially exhausted, and 15 thereupon bears against the rear portion of the feeler and insures its movement longitudinally of the shuttle, and means for replenishing the filling when the feeler is so moved on a detecting beat.
- 20 13. In a feeler mechanism for looms, the combination of a feeler that is supported for movement toward and from the front of the loom and also in a direction longitudinally of the shuttle, a feeler displacer that

is supported in a position inclined to the feeler and to move frontwardly and longitudinally of the shuttle and tends to move longitudinally of the shuttle on each detecting beat as it is pushed frontwardly by a surface in the shuttle and to move the feeler 35 longitudinally of the shuttle, but is prevented from effecting such movement by engagement of the feeler with the filling until the filling is substantially exhausted.

14. In a feeler mechanism for looms, the combination of a feeler that is supported for movement toward and from the front of the loom and also in a direction longitudinally of the shuttle, a feeler displacer that is supported in a position inclined to the 40 feeler and for engagement with the filling, and which on each detecting beat tends to move the feeler in a direction longitudinally along the filling carrier, but is prevented from effecting such movement by engagement of the feeler with the filling until the filling is substantially exhausted, and means for varying the relative inclination of the 45 feeler displacer and feeler.

In testimony whereof I have signed my 50 name to this specification.

ISAAC SNOW.
